Primary Examiner — Mary Ann Calabrese*Assistant Examiner* — Mark David Wolfley(74) *Attorney, Agent, or Firm* — WHDA, LLP(57) **CLAIM**

The ornamental design for a vehicle seat as shown and described.

DESCRIPTION

FIG. 1 is a front elevational view of a vehicle seat, showing our new design.

FIG. 2 is a rear elevational view thereof.

FIG. 3 is a right side elevation view thereof.

FIG. 4 is a left side elevation view thereof.

FIG. 5 is a top plan view thereof.

FIG. 6 is a bottom view thereof.

FIG. 7 is a top front and right side perspective view thereof; and,

FIG. 8 is a top rear and left side perspective view thereof. The broken lines shown in the drawings depict portions of the vehicle seat that form no part of the claimed design. The article of this design is a seat for an automobile, a railroad car, an aircraft, and other vehicle.
